UNITED STATES PATENT OFFICE

2,515,408

INCINERATOR WITH ATTACHED DRYING CHAMBER

Verne D. Jester, Glendale, Calif.

Application June 21, 1948, Serial No. 34,307

6 Claims. (Cl. 110—8)

1

This invention relates to incinerators such as commonly used in the back yard of the average city dweller and has for its object to provide a device of this description of simple and economic construction. More particularly it is the object of the invention to provide improvements in the arrangement and construction of the various parts of the incinerator.

Many occupants of city dwellings develop a habit of mixing fresh garbage in with the paper and other rubbish for the disposal of which the incinerator is designed, only to find that the heat developed in burning the paper and rubbish is insufficient to fire the garbage, which merely becomes cooked and so thoroughly imbedded in the ashes within the incinerator that the device becomes very difficult to clean out.

It is in view of this condition another object of the present invention to provide, within an incinerator, means for separately drying such fresh garbage to the end that it may be prepared for subsequent burning and complete consummation. A further object is to provide improved construction of the walls of the incinerator.

These and other objects of the invention, together with the many advantageous features thereof, will hereinafter be fully described and reference is invited to the accompanying drawing in which a preferred form of the invention is illustrated.

In the drawings:

Fig. 1 is a perspective side elevational view of an incinerator and garbage drying combination embodying the invention, a portion of the outer wall of the device being broken away for the sake of clearness.

Fig. 2 is a cross-sectional side view taken substantially through the center of the incinerator; and

Fig. 3 is a fragmentary view of some parts of the device hereinafter more fully described.

As shown in the drawings, the device of the invention includes a rectangular casing, the walls of which preferably include an outer facing 2 and inner facing 3 both of suitable fire and rust resisting metal; and a layer of insulating material 4 is placed between the two facings. In addition, it may be found advisable to cover the exposed portions of the inner facings with concrete or fire brick lining 13, as indicated in Fig. 2. The upper front corner of the casing is cut open to make room for a closure 5, which is hung on a pivot 6 transversely extending through the casing and fitted at one end thereof with a hand lever 7. This lever may be manually operated to tilt the

2

closure into open position substantially as indicated in Fig. 2. When in closed position, the upper edge of this closure engages a transversely directed ledge 8 at the top of the casing so as to prevent heat and flame from issuing forth from the incinerator at this point. When the closure is fully opened, the material to be burned is conveniently dropped through the opening below the hinge thereof.

10 A screen 10 is fitted across the back wall of the incinerator, at the top thereof, for the purpose of inducing proper air circulation through the device and a rectangular opening 11 is provided at the bottom of the casing, in the front wall thereof, 15 to induce updraft through the casing and for removal of ashes therefrom. I have found, however, that such removal of ashes is frequently quite difficult and for this reason prefer to provide a drawer 12, which is fittingly mounted within the 20 bottom of the casing, for extension through the opening 11. When such drawer is provided, the difficulty of removing ashes is substantially eliminated. In addition, a screen or damper should be horizontally mounted at the bottom of the casing 25 above said drawer space, but as such screens are commonly used, it is not thought necessary to complicate the drawing by illustration thereof.

A receptacle 15 is secured to the rear wall of the casing, of a size and shape to receive therein such garbage as it is desired to dry out as a preliminary 30 to burning the dried garbage within the incinerator. The inner wall of this receptacle takes the shape of a panel 16, which is made with a multiplicity of perforations 17 of a size most suitable for garbage drying purposes. When such foraminous panel is provided, it is found that the heat generated during the burning of the paper and rubbish is sufficient thoroughly to dehydrate the garbage and completely to prepare it for subsequent firing.

35 A panel 16^a is shown mounted to swing on a pivot 19, at the lower end of the panel 16 and it extends downwardly and rearwardly from this pivot to the rear wall of the receptacle. A hand lever 20 is secured to the end of this pivot for the 40 purpose of tilting the panel to permit the material within the receptacle to drop into the lower portion of the incinerator casing, substantially as indicated in Fig. 2. When it is desired to lock the panel in this tilted position it is merely required 45 to provide a stop, such as a pawl 18, which may be manually swung into the path of return of the hand lever. The top opening of the receptacle is 50 closed by a lid 21, which is pivotally hung at 22 and fitted with a hand lever 23 for convenience

in raising the lid for the purpose of filling or cleaning the receptacle.

It is seen from the foregoing description that I have provided a very simple, compact and conveniently operable incinerating and garbage drying combination. It is further to be observed that when the casing of the incinerator is made out of sheet metal with insulating material between the layers thereof, a very light and substantial device is obtained, which may conveniently be moved from place to place and which will give service over a long period of time. But while I have in the drawings illustrated a preferred form of the invention, I do not desire to be limited to the exact sizes, proportions and arrangements shown, but reserve the right to embody such modification as will fall within the claims hereto appended.

It may, for example, be preferred in cases where additional weight is not objectionable to adhere to the conventional method of all-concrete construction. But such concrete incinerators must, of course, be shipped in dismounted condition and manually assembled, whereas my sheet metal incinerator can be manufactured and shipped as a unit.

I claim:

1. An incinerator comprising, a casing having in its front wall an inlet opening at the upper end thereof and a discharge opening at the bottom, the interior of said casing constituting a firebox, a receptacle for garbage secured to and projecting from the rear wall of said casing, a portion of the rear wall of the casing being removed to form an opening into the firebox thereof, a foraminous plate closing the upper portion of said opening, a foraminous panel pivotally hung in said rear wall opening of the casing and downwardly extending from the bottom edge of said plate to form a partition between the receptacle and firebox, a hinged cover for said receptacle, and a hand lever for oscillating said panel on its pivot, thereby to open the bottom of the receptacle for discharge of its contents into the firebox.

2. An incinerator comprising, a casing having in its front wall an inlet opening at the upper end thereof and a discharge opening at the bottom, the interior of said casing constituting a firebox, a receptacle for garbage secured to and projecting from the rear wall of said casing, a portion of the rear wall of the casing being removed to form an opening into the firebox thereof, a foraminous plate closing the upper portion of said opening, a foraminous panel pivotally hung in said rear wall opening of the casing and downwardly extending from the bottom edge of said plate to form a partition between the receptacle and firebox, and a hand lever for oscillating said panel on its pivot, thereby to open the bottom of the receptacle for discharge of its contents into the firebox.

3. An incinerator comprising, a casing having in its front wall an inlet opening at the upper end thereof and a discharge opening at the bottom, the interior of said casing constituting a firebox, a receptacle for garbage secured to and projecting from the rear wall of said casing, a portion of the rear wall of the casing being removed to form an opening into the firebox thereof, a foraminous plate closing the upper portion of said opening, a foraminous panel pivotally hung in said rear wall opening of the casing and

downwardly extending from the bottom edge of said plate to form a partition between the receptacle and firebox, a hand lever for oscillating said panel on its pivot, thereby to open the bottom of the receptacle for discharge of its contents into the firebox, and a latch for maintaining the panel in open position.

4. An incinerator comprising, a rectangular casing the walls of which are made from sheets of metal, sheets of insulating material between said metal sheets, the casing having an exhaust opening in the upper portion of its rear wall and a second opening below said first named opening, a framing projecting from the rear wall of the casing in line with said second opening, a foraminous plate closing the upper portion of the opening, a foraminous panel pivotally hung in the rear casing wall, to close the lower portion of said second opening, and thereby to form a garbage receptacle within said framing, and a hand lever for tilting the panel to open the passage to the interior of the casing for discharge of garbage thereinto.

5. An incinerator comprising, a rectangular casing the walls of which are made from sheets of metal, sheets of insulating material between said metal sheets, the casing having an exhaust opening in the upper portion of its rear wall and a second opening below said first named opening, a framing projecting from the rear wall of the casing in line with said second opening, a foraminous plate closing the upper portion of the opening, a foraminous panel pivotally hung in the rear casing wall to close the lower portion of said second opening and thereby to form a garbage receptacle within said framing, a hinged cover for said framing, and a hand lever for tilting the panel to open the passage to the interior of the casing for discharge of garbage thereinto.

6. An incinerator comprising, a rectangular casing the walls of which are made from sheets of metal, sheets of insulating material between said metal sheets, the casing having an exhaust opening in the upper portion of its rear wall and a second opening below said first named opening, a framing projecting from the rear wall of the casing in line with said second opening, a foraminous plate closing the upper portion of the opening, a foraminous panel pivotally hung in the rear casing wall to close the lower portion of said second opening and thereby to form a garbage receptacle within said framing, a hand lever for tilting the panel to open the passage to the exterior of the casing for discharge of garbage thereinto, and means for locking said panel in closed position.
